UNITED STATES PATENT OFFICE.

CHARLES EDWARD CAMERON, OF PHILADELPHIA, PENNSYLVANIA.

HAME.

No. 904,306.

Specification of Letters Patent.

Patented Nov. 17, 1908.

Application filed June 23, 1908. Serial No. 439,913.

To all whom it may concern:

Be it known that I, CHARLES EDWARD CAMERON, a citizen of the United States, residing at Philadelphia, in the county of 5 Philadelphia and State of Pennsylvania, have invented certain new and useful Improvements in Hames, of which the following is a specification.

It is the object of my invention to lessen 10 the cost of manufacture and enhance the strength and durability of hames.

In the accompanying drawings I illustrate 15 my invention as embodied in a hame externally in the form of the well known Scotch type,—but obviously with suitable modification in detail it may be employed in the construction of hames of other types.

In the accompanying drawings, Figure I is a view in side elevation of a hame, the 20 portion of the filler shell within the main shell being indicated in profile by a dotted line. Fig. II is a view of the same, in edge elevation, sight being taken toward the right hand side of the structure of Fig. I. Fig. 25 III is a longitudinal sectional elevation on the line III—III of Fig. II. Figs. IV, V, VI, and VII are sectional elevations of the structure, sections being supposed taken for the respective figures on the lines IV—IV, 30 V—V, VI—VI, and VII—VII, respectively.

Similar letters of reference indicate corresponding parts.

The body of my improved hame is in the preferred embodiment of my invention illustrated in the above mentioned drawings produced by the union of two metal shells each trough gutter or U-shaped in transverse section, one of which I term the main shell, *a*, and the other the filler shell, *d*, arranged 35 with their concavities in opposition and with the side walls of the one extended between and in lateral contact with those of the other. In the arrangement depicted the walls of the one shell overlie so to speak 40 those of the other, so that the wall edges of the one shell are out of registry with the wall edges of the other.

In practice the shells, which are preferably made of steel, may be conveniently 45 stamped by dies or hammered from suitably shaped flat strips into the axial conformation and trough-shaped section required. The main shell embodies the usual outward and inward axial curves at its upper and 50 lower ends respectively, and the filler shell

embodies an axial inward curve at its lower end.

The curved axial line of the completed hame is in a plane which is in parallelism with the side walls of the shells at the central part of the hame, and, as seen in Fig. I, the basal portion of the filler shell forms the concave or inner face and the basal portion of the main shell the convex or outer face of the curved region in the lower part of the 60 hame. While both of the shells are of a general trough or U-shape in transverse section, each, in the preferred embodiment illustrated, has a special further conformation, as follows: The body of the main shell 65 is for a suitable distance as to its basal wall flat from edge to edge, that is to say, in transverse section said wall exists in a plane at a right angle with respect to the side walls *b*, *c*, of the said shell, and said basal 70 wall is in the assemblage of the shells encountered by the edges of the side walls, *e*, *f*, of the filler shell, *d*, the contact of said side walls with said basal wall,—which latter serves so to speak as a stop for the filler 75 shell,—maintaining the parts in position 80 against displacement by external pressure on the base of either shell.

The filler shell in transverse section is as to one wall, *e*, approximately straight from 85 edge to base, and as to the other, *f*, straight as to its outer ~~on~~ edge region and in substantial parallelism with said wall *e* and curved as to its basal region, so that it externally 90 approximates the form of the wooden filler blocks hitherto employed, and which the filler shell is designed to replace. Both walls of the filler shell gradually increase in height from their ends toward their central 95 portions, as shown more particularly in Fig. I. The shanks of a staple, *g*, a bolt, *h*, the outer end of which carries a line ring, *i*, and one shank of a staple, *j*, extend as rivets through both shells, and being upset at their inner ends, secure the shell members firmly 100 together, reinforcing the hold of the main shell upon the filler shell.

The opposing edges of the end regions of the main shell as distinguished from the body region are brought together as shown 105 in Fig. II, so that said end regions are approximately circular in transverse section. Preferably the upper end region is inclosed by a tube or horn, *k*, of thin ornamental metal beneath which the upper end of the 110

filler shell extends so that a practically complete closure of the interior is secured. The edges of the lower end of the main shell slightly overlap and the lower end of the 5 filler shell may extend slightly beneath the overlapped edges. An eye, *m*, with a suitable shank, *n*, may be formed as a separate structure and said shank extended and secured within the tubular lower end of the 10 main shell to support the eye below said shell.

As will be observed, especially from Figs. IV, and VII the side wall *c* of the main shell is, where the arrangement and proportions of 15 the parts permit, bent as to its outer edge slightly inward to follow the conformation of the curved wall of the filler shell.

The shells are stamped out with great rapidity, and, being shaped in forming dies, 20 the desired configuration may be imparted with accuracy, and the formed shells quickly and easily assembled. The completed structure is strong and durable even though comparatively thin metal be used in making it.

25 In the preferred embodiment of my invention illustrated, the walls of the main shell are, in the region of the deeper portion of the hame, for example the region between the section lines V—V and VI—VI of Fig. I, in transverse section, approximately 30 parallel and perpendicular to the base of said shell, and also, in the same region, the portions of the walls of the filler shell in the vicinity of the outer edges of said walls (being the edges which are in the assembled 35 position of the parts adjacent to the base of the main shell) are, in transverse section, approximately in parallelism with each other and with the walls of the main shell 40 which their side faces confront or oppose; at points in the vicinity of the ends however the side walls of the main shell gradually merge into the substantially annular form of said ends. When in the claims I refer to 45 walls as being straight or flat, it will be understood that the phraseology covers such reasonable variation from mathematical accuracy as the form of the hame manufactured and convenience of manufacture may 50 dictate.

Having thus described my invention, I claim and desire to secure by Letters Patent:

1. A metal filler shell for a hame, approximately trough shaped in transverse section 55 and having side walls of substantially equal height one wall being substantially straight from edge to base and the other curved as to its base.

2. A metal filler shell for a hame, the 60 same being approximately trough shaped in transverse section and having side walls of substantially the same height one wall being approximately straight from edge to base and the other having a straight region at its 65 edge portion and a curved region at its base.

3. A hame comprising a metal main shell, having suitably arranged end regions and a central body which is approximately trough shaped in section, and a hollow metal filler shell arranged within said central body and extending substantially from end to end thereof, with the exterior faces of the side walls of said filler shell opposing the inner faces of the walls of the main shell. 70

4. A hame comprising a main shell embodying end regions and a central region or body which latter is of approximately trough shaped section, and a hollow metal filler shell extending substantially from end to end of said central body and embraced 80 between its side walls and reaching to the bases of the same.

5. A hame comprising a metal main shell having suitably arranged end regions and a central body which is of approximately 85 trough shaped cross section, and a hollow metal filler shell arranged within said central body and extending substantially from end to end thereof, with the exterior faces of the side walls of said filler shell opposing the inner faces of the walls of the main shell, said central body having a curvature in its length the basal portions of the respective shells constituting the respective 90 convex and concave faces of such curved portion.

6. A hame the body of which is formed of a main shell and a filler shell, both of metal, and approximately trough shaped in transverse section, arranged and secured with 100 their concavities in opposition, the side walls of the two shells mutually overlapping with the edges of the one shell out of registry with the edges of the other.

7. A hame the hollow central region or body of which comprises a main shell and a filler shell, both of metal, and both approximately trough shaped in transverse section, arranged and secured with their 105 concavities in opposition, the side walls of the filler shell extending between the side walls of the main shell with the edges of the walls of the main shell out of registry with the edges of the walls of the filler shell, a provision for limiting the inward movement of the filler shell within the main shell, and the end regions of which hame include 110 portions of the main shell which extend beyond the filler shell. 115

8. A hame the body region of which comprises a hollow metal main shell and a hollow metal filler shell both approximately 120 trough shaped in transverse section, said main shell having a base which is in sector at approximately a right angle with respect to its side walls, which shells are arranged and secured with their concavities in opposition, and with the side walls of the filler shell between those of the main shell and in contact with the base of the main shell. 130

9. A hame comprising a metal main shell the ends of which have usual form and equipment, the central body of which is trough shaped in transverse section with a 5 base flat in section, a metal filler shell of length substantially equal to that of the trough shaped central body of the main shell and approximately trough shaped in transverse section, said filler shell being set between the side walls of the central portion 10 of the main shell, the lip or edge of a side wall of the said filler shell being in contact with said flat base of the main shell, and rivets which fasten the shells together.
- 15 10. A hame the body of which is formed of a main shell and a filler shell, both of metal and approximately trough shaped in transverse section, arranged and secured with their concavities in opposition, said 20 main shell having in section a flat base, and said filler shell having in section one wall approximately flat from edge to base and

another curved as to its base, the edges of which walls are in contact with said flat base.

11. A hame the body of which is formed of a main shell and a filler shell, both of metal, and approximately trough shaped in section, arranged and secured with their concavities in opposition, the side walls of 30 the two shells mutually overlapping with the edges of the walls of the filler shell out of registry with the edges of the walls of the main shell, said body embodying a curved region of which the basal portions of the 35 respective shells constitute the concave and convex faces respectively.

In testimony whereof I affix my signature, in presence of two witnesses.

CHARLES EDWARD CAMERON.
